LOADING OF SEWER PIPE, BUILDING TILE,
ETC., FOR RAILWAY SHIPMENTIvan H. Spoor, La Grange, Ill., assignor to The
Gerrard Company, Inc., Chicago, Ill., a corpo-
ration of Delaware

Application June 25, 1931, Serial No. 546,747

8 Claims. (Cl. 105—367)

This invention has to do with the loading of sewer pipe in railway cars, and is particularly concerned with the way in which the pipe is arranged and secured within the car.

5 The principal object of the invention is to provide an improved way of arranging and securing the pipe within the car, whereby to facilitate loading and reduce breakage of the pipe in transit.

10 The method of the invention is especially applicable to the larger sizes of sewer pipe, but may also be employed with the smaller sizes, and with other objects of generally similar character. The method is easy to employ, costs little to practice, and can be used to materially reduce the loss ordinarily occasioned by breakage.

15 While the foregoing statements are indicative in a general way of the nature of the invention, other objects and advantages will be apparent to those skilled in the art upon a full understanding of the improved load arrangement.

20 Three slightly different load arrangements embodying the invention are presented herein by way of illustration, but it will of course be understood that the invention is capable of being embodied in other modified forms coming equally within the scope of the appended claims.

In the accompanying drawing:

Fig. 1 is a horizontal section through a railway car, showing sewer pipe loaded in accordance with the invention;

Fig. 2 is a vertical longitudinal section through the car, taken on the line 2—2 of Fig. 1, showing the load in side elevation;

Fig. 3 is a vertical transverse section through the car, taken on the line 3—3 of Fig. 2, showing the load in end elevation;

Fig. 4 is a view corresponding to Fig. 1, showing a slightly different load arrangement which also embodies the invention;

40 Fig. 5 is a vertical transverse section through one end of the car shown in Fig. 4, showing the modified load in end elevation; and

Fig. 6 shows, in end elevation, a load arrangement which is somewhat similar to that shown in Figs. 1 to 3 inclusive.

45 The load arrangement shown in Figs. 1 to 3 inclusive will first be described. As will be observed in these views, the car 10 is loaded with bell-end sewer pipe 11 of rather large and squatly form.

50 The sections of pipe are all placed on end and are grouped into a long generally rectangular lower deck formation 12 and two short generally rectangular upper deck formations 13 and 14. The ends 15 of the lower deck are spaced a short distance from the ends 16 of the car. The outer ends 17 of the upper decks are set in a little from the ends 15 of the lower deck, while the inner ends 18 of the upper decks are separated somewhat from each other.

60 The sections of pipe in the lower deck 12 are

preferably arranged in rows which extend both transversely and longitudinally of the car. Each of the sections in each row is preferably positioned with the bell end thereof in contact with the spigot ends of the adjacent sections in that row. 5 The lower ends of the sections are preferably supported clear of the car floor on a number of boards 19 which extend longitudinally of the car. The sections in the lower deck are bound tightly together, top and bottom, by tensioned bands 20, 10 which bands are preferably connected at intervals by spacing members 21.

After the lower deck 12 has been completed, several boards 22 are placed thereon longitudinally of the car and the sections of pipe for the 15 two short upper decks 13 and 14 are then placed on the boards 22. The boards 22 are preferably maintained in properly spaced relation to each other by transversely extending cleats 22' at the ends of the boards. The sections in each of the 20 upper decks are arranged and bound together in substantially the same manner as the sections in the lower deck.

During transit, the entire load is free to shift longitudinally of the car as a unit under severe 25 impacts, and the upper decks are also free to shift with respect to the lower supporting deck on the boards 22. The weight of the load, however, will prevent any substantial movement under all but the most severe impacts. If desired, several cleats 30 23 may be fastened to the ends 16 of the car at appropriate heights to serve as limiting abutments for the upper and lower decks should the load by any chance shift that far in the car.

In the form of the invention shown in Figs. 4 35 and 5, the lower deck 24 is made up in the same way as the lower deck in the form already described, and the upper deck 25 is made up in substantially the same way as the lower deck 24. 40 Both decks are preferably coextensive in size and are confined between two end gates 26, which gates are spaced from the ends of the car. The wires 27 with which the sections of pipe in the lower deck 24 are bound together pass about the end gates and the wires 28 with which the sections in the upper deck are bound together likewise pass about the end gates.

Instead of having the wires 27 and 28 extend the full lengths of the decks, from one end of the load to the other, such wires may be passed through the 50 decks and returned, the wires in engagement with the left hand end gate being passed through the decks beyond the center of the latter at 29 and the wires in engagement with the right hand end gate being lapped with the other wires for a 55 distance at the center of the load and passed through the decks at 30. This overlapping double loop arrangement of the wires ties in the sections of pipe quite securely at the door locations 31 and also divides up the strain on the wires. 60

The modified load arrangement which is shown in end elevation in Fig. 6 is substantially the same as that shown in Figs. 1 to 3 inclusive except for the fact that the sections of pipe are grouped together more compactly by resting the spigot ends 32 of alternate sections on the shoulders provided by the bell ends 33 of the adjoining sections. As in the load shown in Figs. 1 to 3 inclusive, the sections in the upper deck are placed upon longitudinally extending planks 34 which are placed on the tops of the sections in the lower deck. Some of the planks used are preferably of larger size than others in order to compensate for the elevations of the alternate sections in each cross row. If desired, longitudinally extending strips 35 may be secured to the sides of the car to prevent any substantial sidewise movement of the load.

I claim:

- 20 1. The method of loading elongated objects, such as sewer pipe, building tile and the like, for shipment in railway cars, which consists in placing a large number of the objects on end in side-by-side relation to each other in an elongated deck formation spaced from the ends of the car, binding all of the objects in the deck together with longitudinally extending binders, placing longitudinally extending boards on top of the lower deck, and constructing two similarly bound but considerably shorter deck formations of the objects on top of the lower deck, capable of sliding movement longitudinally of the lower deck independently of each other, in longitudinally spaced relation to each other and to the ends of the lower deck, the upper and lower tiers being shiftable as an entire group with respect to the floor of the car and also being shiftable as separate units relative to one another.

2. The method of loading elongated objects, such as sewer pipe, building tile and the like, for shipment in railway cars, which consists in placing a large number of the objects on end in side-by-side relation to each other in an elongated deck formation spaced from the ends of the car, binding all of the objects in the deck together with horizontally disposed binders, placing longitudinally extending boards on top of the deck, and constructing two similarly bound but considerably shorter deck formations of the objects on top of the boards in longitudinally spaced relation to each other and to the ends of the lower deck, the upper and lower tiers being shiftable as an entire group with respect to the floor of the car and also being shiftable as separate units relative to one another.

3. The method of loading elongated objects, such as sewer pipe, building tile and the like, for shipment in railway cars, which consists in placing a large number of the objects on end in side-by-side relation to each other in an elongated deck formation spaced from the ends of the car, and binding all of the objects in the deck together with horizontally disposed binders, with the binders from one end passing through the deck beyond the center of the same, and with the binders from the other end passing through the deck beyond the center of the same in centrally lapped relation to the first mentioned binders, said bound objects being shiftable as a unit along the floor of the car.

4. The method of loading elongated objects, such as sewer pipe, building tile and the like, for shipment in railway cars, which consists in laying longitudinally extending boards on the floor of the car, placing a large number of the objects on end on the boards in side-by-side relation to each other in an elongated deck formation spaced from the ends of the car, with the objects merely resting on the boards, without being fastened down to the same, and binding all of the objects in the deck together with longitudinally extending binders to form of the objects a unit load which is shiftable as a unit longitudinally of the boards, said bound objects being shiftable as a unit along the floor of the car.

5. The method of loading bell-end sewer pipe for shipment in railway cars, which consists in placing a large number of the pieces of pipe on end in side-by-side relation to each other in an elongated deck formation spaced from the ends of the car, with the pieces of pipe arranged in both longitudinally extending and transversely extending rows, and with the bell end of each piece of pipe in engagement with the spigot ends of the adjoining pieces in both rows, and binding all of the objects in the deck together with longitudinally extending binders, said bound objects being shiftable as a unit along the floor of the car.

6. The method of loading elongated objects, such as sewer pipe, building tile and the like, for shipment in railway cars, which consists in grouping the objects into superposed deck formations spaced from the ends of the car, binding the objects in each deck together, and confining the decks between end gates connected with the same, the upper and lower tiers being shiftable as an entire group with respect to the floor of the car and also being shiftable as separate units relative to one another.

7. The method of loading elongated objects, such as sewer pipe, building tile and the like, for shipment in railway cars, which consists in placing a large number of the objects on end in side-by-side relation to each other in an elongated deck formation spaced from the ends of the car, binding all of the objects in the deck together with horizontally disposed binders, placing longitudinally extending boards on top of the deck, connecting the boards together at their ends, and constructing another similarly bound deck of the objects on top of the boards, the upper and lower tiers being shiftable as an entire group with respect to the floor of the car and also being shiftable as separate units relative to one another.

8. The method of loading elongated objects, such as sewer pipe, building tile and the like, for shipment in railway cars, which consists in placing a large number of the objects on end in side-by-side relation to each other in an elongated deck formation spaced from the ends of the car, binding all of the objects in the deck together with longitudinally extending binders, placing longitudinally extending boards on top of such lower deck, and constructing a similarly bound upper deck formation of the objects on top of the lower deck in longitudinally spaced relation to the ends of the lower deck, said lower deck being shiftable as a unit longitudinally of the car, and said upper deck being shiftable both with the lower deck and independently thereof.
